UNITED STATES PATENT OFFICE.

ELMER E. STONER, OF STROUDSBURG, PENNSYLVANIA.

ICE-CUTTING MACHINE.

1,374,777.

Specification of Letters Patent. Patented Apr. 12, 1921.

Application filed June 17, 1919. Serial No. 304,757.

To all whom it may concern:

Be it known that I, ELMER E. STONER, a citizen of the United States, residing at Stroudsburg, in the State of Pennsylvania, have invented new and useful Improvements 5 in Ice-Cutting Machines, of which the following is a specification.

This invention relates to ice cutting apparatus and the principal object of the invention is to provide a plurality of band saws 10 for cutting the ice into blocks.

Another object of the invention is to provide means for feeding the ice to the saws, said feeding means engaging the under face 15 of the cake with means for adjusting said means to suit varying thicknesses of ice.

Still another object of the invention is to provide means whereby a cake of ice will be cut first into a plurality of strips and then 20 said strips will be cut into blocks.

The invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is a plan view of the invention;

Fig. 2 is a section between the feed rollers 35 and the band saws looking toward the saws, Fig. 1;

Fig. 3 is a section between the feed rollers and the saws looking toward the feed rollers, Fig. 1;

Fig. 4. is an end view with one of the saw-supporting frames tilted into inoperative position;

Fig. 5 is a view of the heating means for the device;

45 Figs. 6 and 7 are detailed views.

Fig. 8 is a view of a modification.

In these views 1 indicates the supporting frame which is built in the body of water from which the ice is to be taken and which 50 is of L-shape and through which the blocks of ice are passed to be operated upon by the cutting mechanism. This frame is provided with the uprights 2 and the saw frames 3 are pivotally connected to these up- 55 rights so that the said saw frames may be moved into either a vertical position or a

horizontal position. When in a horizontal position the saws are inoperative and all parts of the mechanism are raised above the water level. As shown, the saw frame 60 is of rectangular shape and its lower member supports the shafts 4 in spaced relation while the upper member supports the shafts 5, each shaft 5 being located directly above one of the lower shafts 4. The shafts 4 and 65 5 have secured thereto the pulleys 6 for supporting the band saws 7. As will be seen, the diameters of the pulleys are such as to support each stretch of the saw the same distance apart so that uniform 70 strips of ice will be cut by said saws. The shafts 5 are driven by the drive shaft 8 which is connected to the shafts 5 by the beveled gears 9. The shaft 8 is connected in any desired manner with any type of 75 motor. In front of the saws I locate the feeding means and such means consist of a plurality of spur wheels 10 mounted on the shaft 11 which has its ends journaled in boxings 12. These boxings are slidably 80 mounted in the depending frames 13 which are secured to the main frame. These depending frames extend downwardly into the water so that the spur wheels will engage the under face of the cake of ice. 85 The means for sliding the boxings to bring the spur wheels against the bottom of the cake of ice consist of a screw-threaded shaft 14 located in each of the frames 13 and having its lower end engaging a screw-threaded hole in a bracket 15. This bracket is slidably connected with the depending frame and carries a coiled spring 16, the upper end of which engages the boxings 12. In this way the boxing is yieldably 90 supported on said bracket and when said bracket is raised or lowered by the rotation of the screw member 14 by means of the handle 17, said boxing and the shaft journaled therein will follow this movement. In 100 this way the spur wheels may be raised and lowered so that they will properly engage the bottom face of the cake of ice and this engagement is yieldable due to the coiled springs. The shaft 11 is connected with the 105 actuating means by the flexible shaft 11'.

As will be seen I place one of the cutting means with the feeding means at a point where one part of the L-shaped frame connects with the other part so that as the cake 110 of ice is driven through this part it will be cut into strips, as shown in Fig. 1. Then as

the block is moved at right angles it will come in engagement with the other cutting means so that the strips will be cut into blocks. As will be seen, the drive shaft 8 5 is extended and is connected with the shaft 8' of the other set by the beveled gears 8^x so that one set will be driven by the other set. I provide heaters 18 which consist of steam coils, adjacent the upper portions of the 10 apparatus so as to keep the same free of ice.

In the modification shown in Fig. 8 the means for feeding the ice to the saws consists of endless chains 20 which pass over sprocket wheels 21 located on shafts 22, one 15 of these shafts being driven in the same manner as shaft 11 is driven. I may also provide small rollers 23 carried by brackets 24 for preventing the ice from pushing the saws rearwardly.

20 It is thought from the foregoing description that the advantages and novel features of my invention will be readily apparent.

I desire it to be understood that I may make changes in the construction and in the 25 combination and arrangement of the several parts, provided that such changes fall within the scope of the appended claims.

What I claim is:—

1. An ice cutting apparatus comprising a 30 supporting frame built in a body of water from which the ice is to be gathered and formed in the shape of a channel through which the blocks of ice are to be passed, a saw frame pivotally mounted in said frame 35 and extending across the channel, said frame having its pivotal points arranged above the water level so that when the frame is swung into horizontal position it will be above the water level, transversely arranged shafts in 40 said saw frame adjacent each side thereof, pulleys on said shafts, band saws carried by said pulleys, means for driving the shafts of one row and manually operated means for swinging the saw frame on its pivot to 45 move the saws into vertical and operative positions or into horizontal and inoperative positions.

2. An apparatus for cutting ice comprising 50 a frame, located in the body of water from which the ice is to be gathered and made in the form of a channel through which the blocks of ice are passed, a saw frame pivotally mounted in the supporting frame and extending across the channel, said 55 frame having its pivots arranged above the water level, a row of transversely arranged

shafts at each side of the saw frame, pulleys carried by said shafts, band saws supported by said pulleys, means for driving one row of shafts and power driven means 60 for feeding the block of ice against the saws.

3. An apparatus for cutting ice comprising a frame, located in the body of water from which the ice is to be gathered and made in the form of a channel through 65 which the blocks of ice are passed, a saw frame pivotally mounted in the supporting frame and extending across the channel, said frame having its pivots arranged above the water level, a row of transversely arranged 70 shafts at each side of the saw frame, pulleys carried by said shaft, band saws supported by said pulleys, means for driving one row of shafts and power driven means 75 for feeding the block of ice against the saws, said means consisting of uprights carried by the supporting frame in front of the saw frame, sliding boxings supported by said uprights, a shaft journaled in said boxings, means carried by the shaft for engaging the under face of the block of ice for forcing it against the saws, yieldable means for supporting the boxings and means for adjusting the boxings vertically.

4. An apparatus for cutting ice comprising 80 a frame located in the body of water from which the ice is to be gathered and made in the form of a channel through which the blocks of ice are passed, a saw frame pivoted in said supporting frame and 85 extending across the channel, saws supported in said saw frames, means for actuating the saws and heating means carried by the saw frame for preventing the formation of 90 ice on the saws and their associated parts. 95

5. An ice cutting machine comprising a supporting frame located in the body of water from which the ice is to be gathered and formed to provide an L-shaped channel 100 through which the ice is passed, a pair of saw frames pivotally mounted in the supporting frame, one in each part of the channel, saws carried by said saw frames, means for actuating the saws and feeding means located in front of each saw frame for feeding 105 the ice against the jaws, one set of saws cutting the block of ice into strips and the other set cutting said strips into small blocks.

In testimony whereof I affix my signature. 110

ELMER E. STONER.
